UNITED STATES PATENT OFFICE.

WILLIAM W. LASKER, OF BROOKLYN, NEW YORK, ASSIGNEE TO POWERS ACCOUNTING MACHINE COMPANY, OF NEW YORK, N. Y., A CORPORATION OF DELAWARE.

TYPE CARRIER.

1,423,438.

Specification of Letters Patent. Patented July 18, 1922.

Original application filed March 28, 1917, Serial No. 158,142. Divided and this application filed April 3, 1918. Serial No. 226,487.

To all whom it may concern:

Be it known that I, WILLIAM W. LASKER, a citizen of the United States, residing in Brooklyn, in the county of Kings and State of New York, have invented certain new and useful Improvements in Type Carriers, of which the following is a specification.

This invention relates to a printing tabulator of the kind adapted to be controlled by perforated cards, and relates more particularly to matter divided from my co-pending application Serial No. 158,142 filed March 28, 1917, for printing tabulators.

The invention herein described relates more particularly to the specific form of type carrier of said printing tabulator; and, therefore, only as much of the printing tabulator is mentioned herein as is necessary to show the relation between the matter of the original application and the matter divided out and described herein.

While herein and in said application minute details of one of many possible embodiments of the inventions are described, the invention is not limited to these since various changes may be made in the details of construction and combination without departing from the spirit and scope of the invention as claimed.

One object of the present invention is to improve generally type carriers of this kind.

Other objects are to provide easily assembled durable and efficient type carrier which can be economically manufactured and which will permit the type to be readily removed and replaced.

Still further objects and advantages of the present improvement will be set forth in the following description and drawings in which, —

Fig. 1 is a side elevation of one of the type segments, type, and an actuating gear for the segment.

Fig. 2 is a side elevation of one of the type segments.

Fig. 3 is a perspective view of one of the retaining plates for the type.

Fig. 4 is a side elevation of one of the driving gears for the type segments.

Fig. 5 is a perspective view of one of the type-pieces.

In said copending application there is shown means for analyzing perforated cards, said means being adapted to raise

from rows of pins those pins that correspond to the perforations in the card being analyzed. Reciprocating rack bars associated with the respective rows of pins and provided with abutments are moved along said rows whereby the rack bar is positioned in accordance with the position of the raised pin and the associated perforation.

Said rack bars are provided with rack teeth which mesh with the gear teeth 10 (Figs. 1 and 4) of the gear wheel 11 secured by means of screws 12 to the type segment 14.

The type segments 14 composed of flat stock such as sheet metal are loosely mounted on a shaft mounted in the frame of the accounting machine and are provided with gear teeth 15 which mesh with the accumulator wheels of the accounting machine. The front edge 16 of the segments 14 are made are shaped and are provided with ten rectangular notches 18 which receive the laterally turned ends 19 of sheet metal type-pieces 20. The inner ends of the type pieces are also provided with a laterally turned end 21 which is arranged to fit within rectangular openings 22 diametrically back of the rectangular notches 18. A flat arc shaped plate 24, is arranged to fit against the type-pieces 20 and to hold the laterally turned ends 19 and 21 thereof in engagement with the notches 18 and openings 22 respectively. The plates 24 are secured to the segment by means of bolts 25. Reading from the upper edge of the type carrying portion of the segment, the type carried thereby read in sequence, the first type being zero, the next "1" the next "2", etc., the last type on the segment being numbered "9".

The type 26, that is, the printing character, is secured to the end 19, of each type-piece 20 and preferably is formed integral with the end 19, of each type-piece 20.

I claim as my invention:

1. In a type carrier, the combination of a flat main portion provided with recesses and openings; and type pieces against the face of said portion and each provided with lateral projections engaging in the notches and recesses respectively.

2. In a type carrier, the combination of a flat main portion provided with notches at its outer edge and with openings in radial alignment with said notches respectively;

- 2
- and type pieces each provided with an outer and an inner laterally turned end engaging in the alined notches and openings respectively.
- 5 3. In a type carrier, the combination of a flat main portion comprising a circular portion formed with an arc-shaped type segment portion provided with rectangular notches at its outer edge and with rectangular openings in radial alinement with said notches respectively; type pieces each provided with an outer and an inner laterally turned end engaging in the alined notches and openings respectively; and an arc-shaped
- 10 plate disposed across said pieces and secured to said segment portion to hold said ends in said notches and seat openings.
4. In a type carrier for co-operation with an accounting machine having accumulator
- 20 gears and actuating rack bars, the combination of a flat main portion comprising a circular portion formed with teeth for engagement with the gears, and an arc-shaped type segment portion provided with rectangular
- 25 notches at its outer edge and with rectangular openings near the inner part thereof in radial alinement with said notches respectively; type pieces having type at the outer end and each provided with an outer and an
- 30 inner laterally turned end engaging in said alined notches and openings respectively; an arc-shaped plate disposed across said pieces and screwed to said segment portion to hold said ends in said notches and seats; and
- 35 gear wheels secured to said circular portions adapted to mesh with the rack-bar.
5. As an article of manufacture, a sheet metal type carrier comprising a circular portion and a type segment extending therefrom, there being recesses in the arcuate periphery of said type segment and perforations in alinement with said recesses and removed therefrom for co-operating with type securing means, and teeth on the periphery
- 45 of said circular portion for co-operating with accumulators, there being a shaft receiving opening central of said circular portion and openings in said circular portion around said shaft receiving opening to receive screws for securing an actuating gear to said circular portion.
6. A type carrier comprising, for association with a printing tabulator having reciprocating rack bars with rack teeth and an accounting machine having accumulator
- 55 wheels with gear teeth, a circular portion and a type segment portion extending therefrom, a gear wheel of smaller diameter than the circular portion secured flat against the circular portion of the type carrier and adapted to mesh with the rack teeth of a printing tabulator rack bar, and teeth formed on the periphery of said circular portion adapted to mesh with the gear teeth of an accumulator wheel. 65
7. A type-carrier composed of flat stock and comprising a circular portion and a type-segment portion having recesses in the periphery thereof and having perforations therethrough in alignment with said recesses, type-pieces composed of flat stock and having their ends bent over for engaging said recesses and perforations, each type-piece having on an end thereof a printing character extending, when the type- 75 piece is in engagement with said type-segment portion, beyond the peripheral edge of the type-segment portion in position for printing, and a plate composed of flat stock for retaining the type-pieces in engagement 80 with the type-segment portion.
8. A sheet metal type-carrier comprising a circular portion and a type-segment portion having recesses in the periphery thereof and having perforations therethrough in alignment with said recesses, sheet metal type-pieces having their ends bent over for engaging said recesses and perforations, each type-piece having on an end thereof a printing character formed integral with 90 the type-piece and extending, when the type-piece is in engagement with said type-segment portion, beyond the peripheral edge of the type-segment portion in position for printing, and means for retaining the type- 95 pieces in engagement with the type-segment portion.

WILLIAM W. LASKER.
